UNITED STATES PATENT OFFICE.

FRIEDRICH ROLAND, OF PATERSON, NEW JERSEY.

LOOM MOVEMENT.

Application filed October 6, 1926. Serial No. 139,863.

This invention relates to improvements in loom motions, and particularly to a movement regulating means for the batten, and it is the principal object of the invention 5 to provide a loom with means for delaying the batten at the end of its motion as much as possible in order to allow the spools as much time as possible to pass through the warp, while allowing the batten to move as 10 quickly as possible towards the harness.

Another object of the invention is the provision of a loom movement of simple and therefore inexpensive construction, and one which may readily be installed in any of 15 the looms of the present day.

A further object of my invention is the provision of a loom movement which is durable, positively acting and efficiently operating.

20 These and other objects of my invention will become more fully known as the description thereof proceeds, and will then be specifically pointed out in the appended claims.

25 In the accompanying drawing, forming a material part of this disclosure:

Fig. 1 is a front elevation of my improved batten movement.

Fig. 2 is a top plan view thereof.

30 As illustrated, the loom frame 10 has journaled therein a shaft 11 for the driving pulley 12 over which a belt 13 is guided for transmitting the power of a motor or other source of power to the batten movement 35 claims.

The shaft 11 carries also a gear 14 in juxtaposition to pulley 12 which meshes with another gear 15 on a shaft 16 journaled also in the loom frame. The gear 15 has an 40 eccentrically arranged pin 17 projecting from its side face into and through a slot 18 in the side of a member 19 extending in the direction of the longitudinal axis thereof. The member 19 has formed at its rear 45 end a stub shaft 20 which carries a bevel gear 21 meshing at one side with a bevel gear 22 on the crank shaft 23 driving the batten, while at the opposite side the bevel gear 21 meshes with a bevel gear face 24

50 of a gear 25 on a shaft journaled in the member 19. This gear 25 in turn meshes with the gear 15, and the gears are of the same size.

The pin 17 carries at its outer end projecting through the slot 18 of the member 19, a head 26 or the like.

The operation of my device will be clearly understood from the above description on hand of the drawing, and it will be apparent, that during the rotation of the gears 14, 15 and 25 the pin of gear 15 will be displaced in the slot 18 of member 19 in such a manner that the slowest motion of the batten operating crank shaft takes place when the pin 17 is near the inner end of the slot of member 19 or closer to the pivot point of said member than to its free outer end, in order to delay the batten movement at the end of its rear motion, as much as possible for allowing the spools as much time as possible to pass through the warp, while not interfering with the quick movement of the batten towards the harness.

It is to be understood, that while I have shown and described the preferred form of my invention as an example of the many ways in which the same is to be practically constructed, such changes as come within the scope of the appended claims may be made in the construction of the minor details of my invention without departure from the spirit thereof.

Having thus described my invention, what I claim as new, and desire to secure by Letters Patent is:

1. A batten operating device for looms comprising a plurality of intermeshing gears journaled on shafts arranged in the frame of the loom, a means for transmitting the power from a source of power to one of said gears, one of said gears having a bevel face, a slotted member having a stub shaft at one end, a bevel gear on said stub shaft meshing with said bevel face, a crank shaft, a bevel gear on said crank shaft in mesh with said last named bevel gear, and a means on one of said gears adapted to engage the slot of said member to delay the batten motion at the inner end of its path for allowing the spools more time for passing through the warp.

2. A batten movement for looms, particularly narrow band looms, comprising a train of gears, shafts for said gears journaled in the loom frame, a slotted member pivoted at its rear end and extending longitudinally to the front faces of the gears of said train of gears, a pin eccentrically projecting from the side face of one of said gears into said slot of the said member, a head on said pin, a plurality of bevel gears adapted to be actuated by said train of gears, and a crank shaft

for operating the batten carrying one of said bevel gears adapted to be delayed by the sliding pin at the rearmost end of its path within the slot of said member for allowing 5 more time for the spools to pass through the warp.

3. In a loom, a device for delaying the batten motion at the end of its rearward path for allowing the spools to pass slowly 10 through the warp, said device comprising a train of gears of equal size in mesh with one another, a means for driving one of said gears, a bevel gear formed at the inner face of the last gear, a member slotted at its side 15 edge and pivoted at its rear end, a stub shaft

formed at this rear end, a bevel gear on said stub shaft in mesh with said bevel face, a crank shaft operating the batten, a bevel gear on said shaft in mesh with said stub shaft gear, an eccentrically projecting pin on 20 the side face of one of said gears projecting in the slot of said member, a head on said pin, said pin adapted to delay the batten movement at the end of its inner path for allowing to the spools more time to pass 25 through the warp.

Signed at New York in the county of New York and State of New York this fourth day of October, A. D. 1926.

FRIEDRICH ROLAND.
